UNITED STATES PATENT OFFICE.

FRED TSCHUDY, OF BIRMINGHAM, ALABAMA.

REVERSING MECHANISM.

1,112,101.

Specification of Letters Patent. Patented Sept. 29, 1914.

Original application filed June 17, 1911, Serial No. 633,848. Divided and this application filed October 30, 1911. Serial No. 657,454.

To all whom it may concern:

Be it known that I, FRED TSCHUDY, a citizen of the United States, and resident of Birmingham, county of Jefferson, and State 5 of Alabama, have invented certain new and useful Improvements in Reversing Mechanisms, of which the following is a specification.

My invention relates to the operation of 10 reversing regenerative furnaces, and has particular relation to novel mechanism by means of which such furnaces may be easily and quickly reversed, all in a single operation.

15 This application is a division of my application, Serial No. 633,848, filed June 17, 1911, entitled "Coke producing plants."

In the operation of by-product coke ovens it is the custom to arrange a large number 20 of such ovens in a battery, often as many as seventy ovens being combined into one coke-producing plant. These ovens are periodically reversed, the principle of operation being similar to that of a regenerative 25 furnace, there being checker work which is alternately heated by the products of combustion and through which gas and air may pass on their way to the burning chambers.

Where such a large number of ovens are 30 arranged and adapted for reversal in unison, it becomes necessary to provide some means whereby such reversal may be carried out quickly and without unnecessary waste of power.

35 One of the principal objects of the present invention, therefore, is to provide an apparatus of such character which shall be simple in construction, as well as powerful and certain in operation.

40 My invention will be more readily understood by reference to the accompanying drawings, wherein—

Figure 1 is a plan view of apparatus such 45 as contemplated by me; Fig. 2 is an end elevation thereof; and Fig. 3 is a side elevation.

This mechanism is composed of the base portion 10, carrying bearings for a longitudinally extending worm shaft 11, and a 50 transverse operating shaft 12. These shafts are adapted for rotation in unison by means of the bevel gears 13, 14. Movement is imparted to the shaft 12 by means of a motor 15, or other suitable means.

Mounted on the worm shaft and adapted 55 for reciprocation thereby, I provide a lever-operating member 16, having an air-valve operating projection 17, and recesses 18, 19. This member 16 is adapted for reciprocation between guides 20, 21, mounted on the base 60 10. In order to provide against contingencies due to failure of motive power, I provide hand operating means such as the chain 22, and hand lever 23. Also mounted on the base 10, by means of the pivot 24, is a rocker 65 25, having divergent projections 26, 27, with which the projection 17 is adapted to cooperate. Also mounted on the base by means of pivots 28, 29, are lever arms 30, 31, connected respectively with gas valve operating 70 chains 32, 33. These chains 32, 33, pass over drums 34, 35, slidably and independently mounted on the shaft 36, the chains terminating in the counter-weights 37, 38.

It will be seen that by this reversing mechanism, the air valves are reversed simultaneously by means of the rocker arm 25, and the chain or cable 39, but that the gas valves operable by means of the levers 30, 31, and chains 32, 33, are operated intermittently. The reason for this will be understood in connection with the following description of operation: Assuming the parts in the position shown in Fig. 1, and assuming that it is desired to reverse the furnace, the motor 15 is started and motion is transmitted to the screw threaded shaft 11. This rotation causes the shifting of the member 16 and immediately thereafter the shifting of the lever arm 30, which will 85 shut off the gas supply from the right hand side of the furnace. But it will be seen that air is still permitted to pass through the furnace and out of the stack. However, as the worm continues to shift the member 16, 90 the projection 17 will contact the end 27, of the rocker 25, and cause the reversal of the air currents in the furnaces; that is, the air valve on the right hand side of the furnace will be closed and the air valve on the 95 left hand side opened. As the screw-threaded shaft continues to turn, the recess 18 will finally receive the lower end of the lever 31, and in turn cause the supplying of gas to the left hand side of the furnace. The 100 motor is then stopped and the normal operation of the furnace resumed until such time as it is necessary to again reverse the 105

same, when the operations heretofore described will be repeated in a reverse direction.

It is contemplated by me that the operation of the motor for causing the reversal of the furnaces shall be automatically caused by a master clock.

It will be understood that although my novel apparatus is particularly adapted for use in connection with a by-product reversing coke oven, it may be used with any regenerative reversing furnace with slight modifications. It will be also understood that many modifications may be made in the apparatus herein described, all without departure from the spirit of my invention.

I claim—

1. A reversing mechanism for furnaces, comprising, in combination, a base member, 20 a shaft, an element mounted for reciprocation with relation to said shaft, an air-valve-operating lever and a gas-valve-operating lever, said levers being adapted for actuation by said reciprocating member, and at 25 different periods in the reciprocation thereof, substantially as described.

2. A reversing mechanism for furnaces, comprising, in combination, a base, a worm shaft mounted in bearings on said base, 30 means for rotating said worm shaft, a member mounted on and adapted to be reciprocated by said worm shaft, gas valve and air-

valve-operating levers associated with said base, said levers being adapted for actuation by the said reciprocating member, substantially as described.

3. A reversing mechanism for furnaces, comprising, in combination, a base, a worm shaft mounted in bearings on said base, means for rotating said worm shaft, a member mounted on and adapted to be reciprocated by said worm shaft, gas valve and air-valve-operating levers associated with said base, said levers being adapted for actuation by said reciprocating member and at different stages in the reciprocation thereof, substantially as described.

4. In a reversing mechanism for furnaces, the combination of a supporting member, a reciprocating member mounted for movement on said supporting member, means for reciprocating said reciprocating member, a plurality of levers associated with said mechanism and having portions adapted to be acted upon by said reciprocating member at different points in its reciprocation, said levers being maintained by said reciprocating member against movement except by said reciprocating member, substantially as described.

FRED TSCHUDY.
